Michael J. Kilgore

UNITED STATES PATENT OFFICE.

FRANK REESE, OF MINNEAPOLIS, MINNESOTA.

WEATHER STRIP FOR INSWINGING CASEMENTS.

Application filed September 11, 1922. Serial No. 587,529.

My invention provides an extremely simple and highly efficient weather strip for inswinging casements and, generally stated, the invention consists of the novel construction, arrangement and combinations of parts hereinafter described and defined in the claim.

Particularly, the invention provides a new and improved form of metallic sill strip 10 for co-operation with a supplemental strip carried by the under edge of the casement. Preferably, the sill strip is of brass and of trough-like form, provided with upstanding inner and outer stop flanges, the latter of 15 which projects above the former and, at its upper edge, has a horizontal extension that projects inward or toward the inside stop flange. Preferably also, the supplemental strip is of copper, bent approximately U-shaped in cross-section and adapted for close 20 engagement with the horizontal extension of the outer stop flange of the sill strip.

In the accompanying drawings, which illustrate the invention in its preferred form, 25 like characters indicate like parts throughout the several views.

Referring to the drawings:

Fig. 1 is a fragmentary vertical section taken through the lower portions of a window frame and casement and showing the improved weather strip applied thereto; and 30

Fig. 2 is a perspective showing portions of the sill strip and supplemental strip removed from working position.

The numeral 3 indicates a window frame comprising a sill 4 and stool 5, and the numeral 6 indicates an inswinging casement or window sash, which will be mounted at one edge on vertical hinges, in the customary 40 way.

The sill strip 7 comprises a flat base plate with upstanding inside and outside stop flanges 8 and 9, the latter having a horizontal extension 10 that projects toward the 45 stop flange 8 in a plane above the upper edge of the latter and terminates short of the vertical plane of said flange 8. The base plate of this sill strip is shown as provided with depending sharp-edged ribs 11 that 50 will be pressed down into the wooden sill 4. Preferably, the base plate of the sill strip projects outward of the channel or trough-like body portion of said strip, so as to completely cover the horizontal upper 55 portion of the sill. Screws 12 serve to tightly clamp the sill strip onto the sill,

with its base plate below the upper surface of the stool 5, but with both flanges 8 and 9, of course, projecting above said stool. The flange 9 is provided with one or more 60 drain holes or passages 13 located immediately adjacent to the upper surface of the base plate of the sill strip.

The supplemental weather strip 14, which is of thin spring metal, being preferably, 65 as above stated, of copper, is bent approximately U-shaped in cross-section with its upper flange projecting considerably outward of its lower flange, and this upper flange, by 70 nails or brads 15, is secured to the under edge of the casement 6. Preferably, the casement 6 is rabbeted at 16 to receive the supplemental strip 14, and inward of said rabbet 16 the under edge of the casement is 75 formed with a lower rabbet 17 that forms a close joint with the inside stop flange 8, when the casement is closed. Preferably, and as shown, the component parts of the sill strip are formed integral and by a process known as "extruding" of metal while in 80 semi-fluid or plastic condition.

When the casement is closed, a perfectly 85 water-tight joint is made between the window sill and casement. In the first place, a very close joint is made between the hook-like or hook-acting supplemental strip and the horizontal flange extension of the sill strip, but if any water should be dashed inward between these, it will be caught in the 90 trough of the sill strip and would run out through the drain passages 13. The close joint above made and the second close joint made between the inside stop flange 8 and the rabbet 17 of the casement, prevent leakage of air either inward or outward. It may 95 be further noted that any water that might leak or pass between the supplemental strip and the horizontal flange extension of the sill strip will be directed downward against the outer stop flange 9 and will immediately run out through the drain passages 13 so that there is no possibility of the water being dashed over the inside stop flange 8. These 100 features above noted produce a very highly efficient, yet extremely simple, weather strip for the lower portions of casements. So far as this invention is concerned, any suitable weather strips may be applied to the vertical edges and top of the casement and window frame, or they may be omitted when desired.

What I claim is:

The combination with a window frame

and a swinging casement, the former having a sill and a stool extending above said sill, of a one-piece metallic sill strip secured to the sill and a supplemental joint strip secured to the inner edge of said casement, said sill strip having upstanding inner and outer flanges, the former of which engages the outer edge of the stool and projects thereabove, said outer flange being located materially inward of the outer edge of the sill strip and the outer face of the casement and having a horizontal inward extension lying in a plane above the upper edge of the inner flange with its inner edge spaced materially outward therefrom, screws securing the sill

strip to the sill and extending through holes in said sill strip, certain of which are between the inner flange and the inner edge of said extension on the outer flange, the under edge of the casement having inner and outer rabbets, the former of which overlaps the inner flange and the latter of which overlaps the inner edge of said extension on the outer flange, said supplemental joint strip being U-shaped in cross section and arranged to engage said extension of the outer flange, and a drain hole in the outer flange. 20 25

In testimony whereof I affix my signature.

FRANK REESE.
